UNITED STATES PATENT OFFICE.

JOHN A. ALVEY, OF ST. LOUIS, MISSOURI, ASSIGNOR, BY MESNE ASSIGNMENTS, TO
ALVEY MANUFACTURING COMPANY, OF ST. LOUIS, MISSOURI, A CORPORATION OF
MISSOURI.

ROLLER-CONVEYER.

1,095,445

Specification of Letters Patent.

Patented May 5, 1914.

Application filed October 4, 1911. Serial No. 652,830.

To all whom it may concern:

Be it known that I, JOHN A. ALVEY, a citizen of the United States of America, residing in the city of St. Louis and State of Missouri, have invented certain new and useful Improvements in Roller-Conveyers, of which the following is a specification.

This invention relates to roller conveyers, and has for its main general object to provide an improved construction, combination and arrangement of parts in devices of this character whereby the same can be simply and economically constructed and rendered durable and efficient in service.

Another object is to provide a conveyer roller of improved construction by means of which goods which are being transported thereby will be automatically centered by its own movement.

Other and further objects will appear in the specification and be specifically pointed out in the appended claim, reference being had to the accompanying drawings exemplifying the invention, and in which,

Figure 1 is a fragmentary side elevation of a conveyer constructed in accordance with the principles of this invention, parts being broken away, and parts being shown in section. Fig. 2 is a fragmentary top plan view of the same. Fig. 3 is a section on line 111—111, Fig. 2. Fig. 4 is a fragmentary top plan view of a modified form of the roller.

Referring more particularly to the drawings, and to the embodiment shown therein, the conveyer as a whole is mounted upon any suitable base or support 1, said support, in the present embodiment, being inclined to adapt the conveyer to transport goods by gravity under the action of their own weight. Throughout the length of the conveyer, it is mounted upon its support by a series of substantially U-shaped tie rods 2, which may be secured to the base or support 1 in any suitable manner, not shown in the drawings.

Extending longitudinally of the conveyer, and secured to the upper extremities of the tie rods, are a pair of spaced guide rails or channel bars 3, said rails being held in position by means of rivets 4. Also extending

longitudinally of the conveyer and seated in the corners of the U-shaped tie rods, is another pair of channel bars 5 which, together with the guide rails 3, serve to connect the U-shaped tie rods together to form a rigid conveyer frame.

As shown best in Fig. 3, each of the rollers is constructed, preferably, of a seamless tube 6, within each end of which, is mounted, preferably by a shrinking fit, a bearing block 7 with a central well, or bearing, 8 for the reception of a stub-end journal 9 on the end of a threaded stud 10 which is inserted through an aperture in the web 65 of the channel beam 5, and locked in position by means of a pair of locking nuts 11, which impinge the opposite faces of said web. The flat face of the central bearing well in the block 7 is provided with a depression for seating a ball 12 for taking up the end thrust between the journal 9 and the bearing block 7. The channel beams 5 are secured in position by rivets 18 which also pass through the different tie rods 2. 75

In order to provide improved means for automatically centering goods which are transported by the conveyer, each of the rollers 6 is provided on its outer cylindrical surface with a central rib, or annulus, 19 80 into which merge from opposite directions a pair of helical threads or guides 20 which, by the direction of rotation indicated by the arrow in Fig. 2, serve to impart a lateral impulse toward the center of the rollers. 85

In the modification shown in Fig. 4, a pair of centrally disposed ribs 21 are spaced apart, each having its separate helical guide 22 merging therewith.

What I claim is:

In a roller conveyer, a roller rotatably mounted, said roller being provided with helical guides on its periphery, said helical guides starting adjacent the ends of said roller and leading to the center and intersecting with an annular guide at the center of said roller.

JOHN A. ALVEY.

In the presence of—

HUGH H. ALVEY,
M. C. HAMMON.
